UNITED STATES PATENT OFFICE.

CLEMENT ZOPHY, OF WEST ALLIS, WISCONSIN.

CEMENT-BLOCK MACHINE.

Application filed June 9, 1922. Serial No. 566,993.

To all whom it may concern:

Be it known that I, CLEMENT ZOPHY, a citizen of the United States, and resident of West Allis, in the county of Milwaukee and State of Wisconsin, have invented new and useful Improvements in Cement-Block Machines, of which the following is a description, reference being had to the accompanying drawings, which are a part of 10 this specification.

This invention relates to cement block machines and has for one of its objects to provide a machine adapted to mold cement blocks having core spaces, which 15 blocks may or may not be formed with imitation stone surfaces.

A further object of the invention is to improve certain of the prior devices of this character whereby a machine may be 20 produced which will be simple in construction, comparatively inexpensive to manufacture, and more efficient in use than those which have been heretofore proposed.

With the above and other objects in view 25 which will appear as the description proceeds the invention consists in the novel details of construction and combinations of parts more fully hereinafter disclosed and particularly pointed out in the appended 30 claims.

In the accompanying drawings in which like numerals designate like parts in all the views;

Figure 1 is a side elevational view of a 35 machine made in accordance with the present invention, all of the parts being shown in their closed positions;

Fig. 2 is an end elevational view of the parts shown in Fig. 1 as seen from the 40 right of the said figure;

Fig. 3 is a central vertical sectional view of the machine, the mold being shown in its open position; and

Fig. 4 is an elevational view of the parts 45 in their positions illustrated in Fig. 3.

Referring to the drawings the numeral 5 indicates a suitable frame upon which is supported a substantially upright casing 6 of a size and shape to correspond with the 50 size and shape of the concrete block which is to be made. The said casing 6 is provided with a movable bottom plate 7 which is supported upon the vertically disposed rods 8 which pass through suitable guide-ways 9 at the bottom of the said casing and are 55 connected together by means of a yoke 10,

as will be clear from Fig. 3. This said yoke 10 is rigidly connected to the transversely extending bar 11 which is adapted to move in the vertical slots 12 with which the frame 5 is provided, and the ends of the said bar have rigidly secured to them the vertically extending members 13, as will be readily apparent.

The upper ends of the members 13 have 65 pivotally secured to them, as at 14, one end of the links 15, the other ends of the said links being pivotally secured, as at 16, to one end of the lever arms 17 which are carried by and rigid with the shafts 18 70 journalled in suitable bearings 19 upon the frame 5. One of the said shafts is provided with an operating lever or handle 20 while the other of the said shafts 18 is provided with a counter-weight 21, as will be 75 clear from Figs. 1, 2, and 4. The said shafts are further provided with the intermeshing gear segments 22 whereby motion imparted to one of the said shafts by means of the handle 20 may be transmitted to the 80 other of said shafts in the well known manner.

Pivottally secured to the movable bottom plate 7, as at 23, is a movable mold member 24 provided with a bottom wall 25, an 85 end wall 26, and a pair of side walls 27. The interior surface of the bottom wall 25 may, if desired, be roughened in order to impart a stone-like surface to the finished block, as will presently appear, and the end 90 wall 26 is provided with an opening 28 adapted to accommodate a core member 29 for the purpose of hollowing out the said blocks. One end of the said core member projects beyond the wall 26, as is best shown 95 in Figs. 1 and 3, and in order to accommodate this projecting end the casing 6 is provided with a slot 30 into which the said projecting end is adapted to move.

Pivottally secured to the casing 6, as at 31, 100 are the bell crank members 32, having the substantially horizontal projecting arms 33 and the substantially vertical arms 34. The said arms 34 are provided with a suitable slip joint 35 whereby they may be extended, 105 and the free ends thereof are pivotally connected as at 36 to one corner of the movable mold member 24, as will be clear from Figs. 1 and 4. The arms 33 of the bell crank members are preferably curved at their free 110 ends substantially as shown, and these said arms are adapted to be engaged by a roller

37 carried by the pivot pin 14, above described.

In operation the parts are positioned substantially as illustrated in Figs. 1 and 2, the core member 29 being positioned within the mold 24 and the movable bottom plate 7 being dropped to its lowest position within the casing 6. Cement, or other suitable plastic material, is then introduced into the mold member 24 and is allowed to set therein. When it is desired to remove the block from the mold the lever 20 is moved in a counter-clockwise direction, as seen in Fig. 1, which movement causes a partial rotation of the shaft 18 carrying in the said lever, and, through the segmental gear connections 22, a partial rotation of the companion shaft 18 on the opposite side of the machine.

The movements of these said shafts are transmitted through the lever arms 17 and pivot connections 16 to the link members 15, and in turn from them through the pivot connections 14 and vertical extending members 13 to the transverse bar 11, which in turn moves the yoke 10, as well as the rods 8 and bottom plate 7 upwardly to the positions shown in Figure 3.

The upward movement of the links 15, vertical members 13, and pivots 14 brings the rollers 37 into contact with the arms 33 of the bell crank members 32 causing the latter to move about their pivots 31 and swing the arms 34 thereof in a counter-clockwise direction, as seen in Figure 1, to the positions illustrated in Figure 4. This causes the mold member 24 to swing about its pivot 23, as will be readily apparent, so that its normally horizontal wall 25 assumes a vertical position, while the wall 26 assumes a horizontal position, as shown in Figs. 3 and 4. When in these positions the core member 29 may be readily removed from the block 40 and the latter itself may be then readily slipped out of the open side of the mold. The parts are then returned to their initial positions illustrated in Fig. 1 whereupon the operation may be repeated.

It is obvious that those skilled in the art may vary the details of construction as well as the arrangement of parts without departing from the spirit of the invention and therefore it is not wished to be limited to the above disclosure except as may be required by the claims.

What is claimed is:

1. A machine of the class described comprising a casing; a mold supporting member within said casing; a mold member pivotally secured to said supporting member; and means for moving said mold and supporting members out of said casing and simultaneously swinging the former about its pivot.

2. A machine of the class described comprising a casing; a movable mold support-

ing member within said casing; a mold member pivotally secured to said supporting member; means for moving said mold and supporting members out of said casing; and means actuated by said last named means for swinging said mold member about its pivot as it emerges from said casing.

3. In a machine for making hollow blocks from plastic material the combination with a casing and a slidable plate member therein, of a mold member pivotally secured to said plate member and adapted to receive and hold a core; means comprising levers pivoted to said casing and mold member for swinging the latter about its pivot; and means for moving said plate member out of said casing, said last named means also engaging said levers to cause the swinging movements of said mold member.

4. In a machine for making hollow blocks from plastic material the combination with a casing and a slidable plate member therein, of a mold member pivotally secured to said plate member and adapted to receive and hold a core; means comprising levers pivoted to said casing and mold member for swinging the latter about its pivot; and means including an oscillating shaft and link connections for moving said plate member out of said casing, said link connections also engaging said levers to cause the swinging movements of said mold member.

5. An apparatus of the class described comprising a frame; a casing mounted on said frame; a movable plate within said casing; a mold member pivotally secured to said plate; connections between said casing and mold member, comprising bell-crank levers pivoted on said casing and connected to said mold member, for swinging the latter about its pivot; a plurality of oscillating shafts carried by said frame; link connections between said shafts and plate for moving the latter into and out of said casing; and means carried by said link connections for engaging one arm of said bell-crank levers to swing said mold member.

6. An apparatus of the class described comprising a frame; a casing mounted on said frame; a movable plate within said casing; a mold member pivotally secured to said plate; connections between said casing and mold member, comprising bell-crank levers pivoted on said casing and provided with an extensible arm connected to said mold member, for swinging the latter about its pivot; a plurality of oscillating shafts carried by said frame; link connections between said shafts and plate for moving the latter into and out of said casing; and means comprising rollers carried by said link connections for engaging one arm of said bell-crank levers to swing said mold member.

In testimony whereof I affix my signature.
CLEMENT ZOPHY,
